UNITED STATES PATENT OFFICE.

JOHN W. WINGERT, OF HOISINGTON, KANSAS.

GARMENT-STAND.

No. 863,820.

Specification of Letters Patent.

Patented Aug. 20, 1907.

Application filed April 19, 1906. Serial No. 312,656.

To all whom it may concern:

Be it known that I, JOHN W. WINGERT, a citizen of the United States, residing at Hoisington, in the county of Barton and State of Kansas, have invented a new and useful Improvement in a Garment-Stand, of which the following is a specification.

This invention relates to garment stands and more particularly to folding stands; the object being to provide a stand for holding coats and pants which can be easily and quickly folded into a very small package so that it can be readily carried in a suit-case or satchel.

Another object of my invention is to provide the stand with an adjustable coat hanger and pants stretching means.

With these various objects in view, my invention consists in the employment of a folding stand having an adjustable coat hanger arranged adjacent its upper end provided with slots to receive the buttons of the pants, clamping means arranged adjacent its lower end adapted to receive the bottom of the pants, said stand being provided with adjusting means for raising the coat hanger for stretching the pants.

The invention consists also of the novel features of construction hereinafter fully described and pointed out in the claims.

In the drawings forming a part of this specification:— Figure 1 is a perspective view of my improved garment stand. Fig. 2 is a detail perspective view. Fig. 3 is a horizontal sectional view. Fig. 4 is a front view of the stand. Fig. 5 is a detail vertical sectional view. Fig. 6 is a perspective view of my improved stand, folded.

Referring to the drawings A, indicates the base of the stand having an upwardly extending tube B, secured thereon, carrying a sleeve C, provided with a set-screw C', and bifurcated apertured spaced lugs C², in which the upper ends of the legs D are pivoted, which are connected to the base A, by braces D'. The base A, is provided with upwardly projecting arms A', having roughened surfaces and are provided with inwardly extending bolts E, on which are slidably mounted arms F, having roughened surfaces and being provided with cam faces adapted to be engaged by cam levers G, mounted on said bolt and securely clamp the arms together.

The upper end of the tube B, is provided with a thumb-screw B', adapted to engage a rod H, mounted therein on the upper end of which is secured a tube I, by a thumb-screw I', having a threaded upper end adapted to fit in a threaded opening in a lug of a ring J, secured in the cap K. Curved plates L, are pivoted to the cap K, by bolts K', forming shoulder-supports which are provided with spaced slots L', along their edges adapted to receive the buttons of the pants, and support the same. The under side of the plates L, are provided with bifurcated apertured lugs L², carrying arms M, the lower ends of which are pivoted in the bi-

furcated apertured lugs N', of the sleeve N, adjustably mounted on the tube I, by a thumb-screw N².

Shoulder members O, provided with spaced slots O' are mounted on screws O², on the under side of the plates L, so that the shoulder can be adjusted to any width desired so as to suit the shoulders of different size coats.

A cap P, is adapted to fit over the cap K, when the stand is set up and is provided with bayonet slots P', at its edge in which the screws L³, of the plate L, are adapted to fit and inclose the stand when in a folded position as shown in Fig. 6, so that it can be readily carried.

From the foregoing description it can be readily seen that by securing the button of the pants in the slots in the plates and clamping the buttons of the pants in the clamp, that the pants can be stretched by adjusting the rod between the tubes.

Having thus fully described my invention, what I claim as new and desire to secure by Letters Patents is:—

1. In a device of the kind described, the combination with a stand provided with a cap, of plates hinged to said cap provided with slots adapted to receive the suspender buttons, of a pair of pants, and means for clamping the bottom of the pants carried by the base of the stand, for the purpose described.

2. In a device of the kind described, the combination with a stand, and a base provided with pants clamping means, of a cap mounted on said stand, plates hinged to said cap provided with slots adapted to receive suspender buttons of pants, sliding outwardly extending members carried by said plates, and means for adjusting said plates, for the purpose described.

3. In a device of the kind described, the combination with a folding stand, of a cap mounted on said stand, curved plates hinged to said cap provided with button securing slots, adjustable members carried by said plates, pants-clamping means carried by the base of the stand and a cap adapted to be locked over the end of said cap, for the purpose described.

4. In a device of the kind described, the combination with a base provided with an upwardly extending tube, of legs carried by said tube connected to said base, arms projecting upwardly from said base provided with bolts, arms slidably mounted on said bolts provided with cam-surfaces, cam levers mounted on said bolts adapted to engage the cam surfaces of the arms, and coat and pants supporting members adjustably mounted on said tube for the purpose described.

5. In a device of the kind described, the combination with a base mounted on legs, of pants clamping arms carried by said base, a tube extending upwardly from said base, a rod mounted in said tube, a tube mounted on said rod provided with a cap, plates hinged to said cap provided with button securing slots, and supporting arms connected to said plates adjustably mounted on said tube, for the purpose described.

6. In a device of the kind described, the combination with a base provided with an upwardly extending tube, of a rod mounted in said tube, a tube mounted on said rod provided with a cap, curved plates hinged to said cap provided with button securing slots, shoulder-members slidably mounted on said plates, supporting arms carried by said plates and pants clamping arms carried by the base for the purpose described.

7. In a device of the kind described, the combination with a base provided with an upwardly extending tube, of a sleeve mounted on said base provided with legs connected to said base, an upwardly extending rod mounted in said base, and a tube adjustably mounted thereon provided with a sleeve, a cap secured on the upper end of said tube, curved outwardly extending arms embracing and pivotally connected at their inner ends to said cap, supporting rods pivotally connected at one end to the inner faces of said 10 curved arms, and at the other end to a sleeve carried by said tube, said curved arms being provided with T-shaped slots for receiving and securely holding the suspender

buttons of pants, extension shoulder plates adapted to fit inside said arms and slidably connected thereto by means of headed bolts passing through said arms, and slots in 15 said plates, a cap adapted to fit over the before mentioned cap when the stand is in an operative position, and adapted to fit over the lower end of said stand when it is in a folded position and means for locking said cap to the lower ends of said arms, for the purpose described.

JOHN W. WINGERT.
